EX

OR D 5,832

UNITED STATES PATENT OFFICE.

WILLIAM MUSHET AND ROBERT MUSHET, OF DALKEITH, SCOTLAND,
ASSIGNORS TO JORDAN L. MOTT, OF MOTT HAVEN, NEW YORK.

DESIGN FOR GARDEN-CHAIRS.

Specification forming part of Design No. 5,832, dated April 30, 1872.

CASE D.

Specification describing a new and original Design for Garden-Chairs, invented by WILLIAM MUSHET and ROBERT MUSHET, of Dalkeith, in the county of Edinburgh, in Scotland.

The nature of our design is fully represented in the accompanying photographic illustration, to which reference is made.

1. We claim the design of the center piece a at the top of the back, as shown.

2. We also claim the design of the arm pieces b, as shown.

3. We also claim the design of the fronts c of the end pieces, and the front legs d, as shown.

4. We also claim the design of the panel e in the end pieces, as shown.

5. We also claim the panel f in the end piece, as shown.

6. We also claim the design of the panels g in the back, as shown.

7. We also claim the design of the center panel h in the back, as shown.

8. We also claim the design of the panels i in the back, as shown.

9. We also claim the entire design for garden-chairs, comprising the several designs above specified, as shown.

The above specification of our invention signed by us this 12th day of January, 1872.

W. MUSHET,

R. MUSHET.
